Specification for Design.

Patented May 19, 1914.

Application filed February 13, 1914. Serial No. 818,611. Term of patent 14 years.

To all whom it may concern:

Be it known that I, CHARLES F. REYNOLDS, a citizen of the United States, residing at Cleveland, Cuyahoga county, Ohio, have invented a new, original, and ornamental Design for Buckles, of which the following is a specification, reference being had to the accompanying drawings, forming part thereof, in which—

Figure 1 is a perspective and Fig. 2 an inverted perspective view of a buckle embodying the design.

I claim:

The ornamental design for a buckle, as shown.

In testimony whereof, I have hereunto set my hand.

CHARLES F. REYNOLDS.
